GLASSWORKING PRESS

Levi F. Goodrich, Corning, N. Y., assignor to Corning Glass Works, Corning, N. Y., a corporation of New York

Application March 16, 1936, Serial No. 69,201

7 Claims. (Cl. 49—35)

This invention relates to improvements in glass working apparatus and particularly to glass pressing mechanisms.

The molds and plungers generally used in glass working apparatus for pressing glass charges into predetermined forms usually have a ring which seats upon the periphery of the upper edge of the mold surrounding the mold cavity. As the molten glass is pressed into shape by the downward travel of the plunger into the mold, it is forced upwardly around the plunger toward the upper edge of the mold and against the mold ring. The ring limits and determines the extent of rise of the glass in the mold and to prevent the glass from checking during the pressing operation, the ring is yieldably held in engagement with the mold by a plurality of compression springs ordinarily carried by the plunger operating mechanism.

The power needed to compress the springs is necessarily high in order to resist the rise of the glass beyond the confines of the mold. With the spring compressing mechanism carried by the plunger operating mechanism, this power has heretofore been supplied directly by the pressman while he was advancing the plunger into the mold cavity and pressing the glass. This arrangement required the pressman to continue applying the pressing force to hold down the mold ring after movement of the plunger had been completed and after the pressing force was no longer required. Due to this fact the force applied to the plunger during the final stage of the pressing operation was difficult to judge accurately, owing to the high pressure required to maintain the springs of the mold ring hold-down mechanism compressed. The result of this was that the quality of the product depended to a large degree upon the skill of the pressman and his response to the feel of the press lever.

It is an object of this invention to reduce to a minimum the power necessary for proper functioning of glass pressing devices during the critical period of the pressing operation.

Another object is the production of pressed glassware of uniformly high quality without having to depend to any great extent upon the skill of the pressman.

Among its features, my invention embodies a mechanism operated in a predetermined sequence during a glass pressing operation to automatically regulate the effectiveness of the pressing operation, in such a manner that the springs of the mold ring compressing mechanism are held compressed without effort by the pressman as soon as the downward stroke of the plunger is substantial-

ly completed, thereby permitting better pressure control during the final and most critical stage of the pressing operation.

Other features include a mold, a plunger, means for advancing the plunger into the mold, a ring seated on the mold and surrounding the plunger, and means actuated upon the advancing stroke of the plunger to hold the ring in contact with the mold independently of the plunger.

The above objects may be attained by the use of my invention which includes the novel construction, combination, and arrangement of parts as fully set forth in the following specification, claimed and illustrated in the accompanying drawings, in which:

Fig. 1 is a front view in elevation of a glass working press embodying my invention, certain portions of which are shown in section;

Fig. 2 is a view similar to Fig. 1 showing the plunger advanced into the mold;

Fig. 3 is a side view of Fig. 2;

Fig. 4 is a transverse sectional view taken on the line 4—4 of Fig. 1;

Fig. 5 is a transverse sectional view taken on the line 5—5 of Fig. 1; and

Fig. 6 is a perspective view of yoke 33 of the assembly.

Referring to the drawings in detail, a bed 10 is supported on legs 11 and provided with standards 12. Slidably mounted on the standards 12 near their upper ends is a power head 13 carrying at opposite ends trunnions 14 to which the upper ends of connecting rods 15 are secured. The lower ends of the connecting rods are pivoted to crank arms 16 carried on opposite ends of a shaft 17 which is journaled in the legs 11 and extends transversely of the machine as illustrated in Fig. 1. Connected to one of the crank arms 16 is a hand lever 18 by means of which the shaft 17 is rotated to exert downward pull on the power head 13. A counter-weight 19 is connected to the crank arms in such a position as to yieldingly urge the power head into elevated position when the press is at rest.

Slidably mounted on the standards 12 in spaced relation to the power head 13 and movable in unison with the latter is a press head 20 carrying a mold plunger 21 which aligns with the cavity 22 of a mold 23 supported upon the bed 10. Connecting the power head 13 with the press head 20 is a rod 24 adjacent the upper ends of which are screw threads 25 for cooperation with adjusting nuts 26 and 27 by means of which the distance between the power head and press head may be accurately adjusted.

Secured to the standards 12, at a point intermediate the power and press heads, is a transversely extending frame 28 which is provided with depending ears 29 to which the upper ends 5 of links 30 are pivoted. The lower ends of these links are pivoted to the upper ends of links 31, the lower ends of which in turn are pivoted to upstanding ears 32 carried by a yoke 33. This yoke is slidable upon the connecting rod 24 and 10 is provided at spaced intervals with openings 34 (Fig. 6) through which spring supporting rods 35 are slidable. The upper ends of these rods are threaded as at 38, while the lower ends are secured to a pressure ring 36 and downward 15 motion of these rods through the openings 34 is limited by nuts 37 which cooperate with the screw threads 38 above mentioned. Compression coiled springs 39 surround the rods and engage the under side of the yoke 33 and the upper side 20 of the pressure ring 36 so as to yieldingly urge the ring 36 downwardly.

Formed intermediate the upper and lower ends 25 of the connecting rod 24 are screw threads 40 for cooperation with adjusting nuts 41 and 42 by means of which a sleeve 43 carrying diametrically opposed radial ears 44 is adjustably connected to the connecting rod 24. Pivoted to the ears 44 of the sleeve 43 are the upper ends of 30 drive links 45 the lower ends of which are pivoted to the junction of the links 30 and 31.

In operation, a charge of glass 46 is deposited in the mold cavity 22 after which a mold ring 47 is positioned on the upper side of the mold 23 surrounding the cavity. The lever 18 is then moved 35 to exert downward pull upon the power head 13, thus causing the plunger 21 to enter the mold cavity to press the glass into the desired form. Simultaneously with the downward motion of the mold plunger 21, the sleeve 43 moves down into the position shown in Fig. 2, thus causing the 40 links 30 and 31 to exert downward pressure upon the yoke 33 until they reach the position shown in Fig. 2. The pressure ring 36 is thus seated on the mold ring 47 with the springs 39 compressed, 45 so as to yieldingly hold the mold ring against the upper face of the mold. The straightening of the links 30 and 31, as illustrated in Fig. 2, takes place slightly before the mold plunger has reached its downward limit of travel so that at 50 the moment the glass contacts the mold ring any upward pressure exerted by the glass against the mold ring is transmitted to the pressure ring 36 through the springs 39 and yoke 33 to the links 30 and 31 and thence directly against the rigidly supported frame 28. With the linkage as provided it will be seen that, after the plunger 21 has reached its downward limit of travel, the 55 only pressure necessary to hold all parts in their relative positions is that required to overcome the opposing force of counterweight 19. By the use of such a press mechanism even an inexperienced pressman can readily feel the release of tension on the press lever as tension of the compressed springs 39 is transferred from rod 24 and cross-member 28, entirely to the cross-member, and is thus able to easily control the pressing force on 60 the plunger at the final and most critical stage of the pressing operation.

While in the foregoing there has been shown and described the preferred embodiment of my 70 invention, it is to be understood that minor changes in the details of construction, combina-

tion, and arrangement of parts may be resorted to without departing from the spirit and scope of my invention as claimed.

I claim:

1. In a glass working press, a mold, a mold ring, a plunger, means to advance the plunger into the mold, a pressure ring surrounding the plunger and movable upon its advance, yieldable elements for cooperation with said pressure ring, and mechanism actuated by said means to advance the pressure ring into contact with the mold ring and to hold it thereon under tension of said yieldable elements independently of said first means.

2. In a glass working press, a mold, a mold ring, yieldable means for holding said mold ring against such mold, a plunger, a common means for advancing said plunger into said mold and for rendering effective said yieldable means, and means excluding said common means for holding 15 said yieldable means effective after the movement of said plunger has been completed.

3. In a glass working press, a mold, a plunger, a mold ring seated on said mold, yieldable hold-down means for said mold ring arranged above 25 said ring, a rod for forcing said plunger into said mold and said yieldable means into compressed engagement with said mold ring, and other means for holding said yieldable means effective after the movement of said plunger has been completed.

4. The method of pressing glass which includes applying pressure to molten glass to cause certain portions thereof to rise, yieldingly restricting the rise of such portions beyond predetermined limits, and separately continuing pressure application to such portions and to the remaining portions of the article during the completion 35 of the pressing cycle.

5. In a glass working press, a mold and a co-operative plunger, means to advance said plunger into said mold, a mold ring, a pressure ring; and mechanism, actuated by said means, which resiliently seats said pressure ring on the mold ring and which also relieves the pressure from said 45 means required to maintain the pressure ring so seated, after said means has advanced said plunger a predetermined distance.

6. In a glass working press, a mold and a co-operative plunger, means to advance said plunger into said mold, a mold ring, a resiliently mounted 50 pressure ring, and means including a system of levers actuated by said first means to seat said pressure ring under tension of its resilient mounting to resiliently hold said mold ring in position on said mold, said latter means being so arranged with respect to said first means that the force required to maintain said pressure ring seated is relieved from said first means at a predetermined stage of movement of such first means.

7. In a glass working press, a mold, a plunger, a rod for advancing said plunger into said mold, a mold ring on said mold, an assembly including a pressure ring, compression springs, and a support, and means including a linkage between said rod and said support adapted to move said assembly as required to bring said pressure ring into engagement with said mold ring, compress said springs, and finally to remove their counter-pressure from said rod during the final stage of 65 movement of the plunger into the mold.

LEVI F. GOODRICH.
